CLAIM

The ornamental design for a sport spoon, as shown and described.

DESCRIPTION

FIG. 1 is a perspective view of the soccer sport spoon with the spoon bowl as a soccer ball and the spoon handle as a soccer lower leg, sock, and shoe showing my design;

FIG. 2 is a top view thereof;

FIG. 3 is a bottom thereof;

FIG. 4 is a front side view thereof;

FIG. 5 is a back side view thereof;

FIG. 6 is a left side view thereof; and,

FIG. 7 is a right side view thereof.

The broken lines shown in FIGS. 1–7 represent the portions of the design which form no part of the claimed design, such as ball seams, transitions, shoe and sock lines.
